UNITED STATES PATENT OFFICE.

AUGUST TOELLE, OF ANDERSON, INDIANA, ASSIGNOR TO REMY ELECTRIC COMPANY, OF ANDERSON, INDIANA, A CORPORATION OF INDIANA.

IGNITION COIL.

Application filed July 7, 1921. Serial No. 482,966.

To all whom it may concern:

Be it known that I, AUGUST TOELLE, a citizen of the United States of America, residing at Anderson, county of Madison, State of Indiana, have invented certain new and useful Improvements in Ignition Coils, of which the following is a full, clear, and exact description.

This invention relates to ignition apparatus for supplying electrical ignition to the cylinders of an internal combustion engine and to an auxiliary appliance such as a liquid fuel burner for heating the engine intake.

One of the objects of the invention is to provide an ignition system including a battery ignition coil and timer for engine ignition and another ignition device for the auxiliary appliance which is constructed to be controlled by the engine ignition timer without change thereto and without interfering with the engine ignition. It is an object to automatically cut down the current consumption by this other ignition device as the speed of the engine increases, and, at a predetermined speed to automatically render this other device inoperative.

Another object is to provide an ignition unit for the auxiliary appliance so constructed that it may be installed with the usual engine ignition equipment by making certain connections therewith but without changing the engine ignition equipment.

In this connection it is a further object to provide a unitary structure including an ignition coil for the auxiliary equipment and control devices for said coil which may be connected onto the regular engine ignition system. In this connection, this invention includes certain improvements in a similar device described and claimed in the copending application of J. T. Fitzsimmons, Serial No. 478,786, filed June 20, 1921.

Other and further objects and advantages of the present invention will be apparent from the following description, reference being had to the accompanying drawings, wherein a preferred embodiment of the present invention is clearly shown.

In the drawings:

Fig. 1 is a wiring diagram of the engine and auxiliary ignition system;

Figs. 2, 3 and 4 are sectional, top and side views, respectively, of an ignition unit for the auxiliary appliance; and

Fig. 5 is a top view thereof showing the vibratory base removed and inverted.

Referring to Fig. 1, a grounded battery 20 is connected by wire 21, ignition switch 22, wire 23, ignition resistance 24 with engine 60 ignition coil 25 having primary 26 and secondary 27, and with grounded timer 28 having contacts 29 and 30 intermittently separated by the operation of the engine. 31 is a condenser in shunt with contacts 29, 30. 65 Distributor 32 connects in recurrent sequence the secondary 27 with engine plugs 33.

The ignition unit for the auxiliary appliance is designated as a whole by numeral 40, and includes a coil 41 having a core 42, primary 43 and secondary 44. Primary 43 is connected by wire 45 with terminal 46 attached by wire 47 to wire 23. The other end of primary 43 is connected by wire 48 to vibrator fulcrum post 49. One end of secondary 44 is grounded at 50 and the other end connected to high tension terminal 51 with which the plug 52 of the auxiliary appliance is connected.

A yoke 53 is magnetically related to core 80 42 and supports core 54 surrounded by holding coil 55. Coil 55 is connected at one end by wire 56 with grounding terminal 57, and, at the other end by wire 58, terminal 59, and wire 60 with timer contact 29.

Post 49 supports armature 61 carrying spring blade 62 carrying contact 63 cooperating with contact 64 carried by grounded adjusting screw 65. Stop 66 carried by armature 61 engages the end of blade 62 to 90 separate contacts 63, 64 upon a predetermined downward movement of armature 61. Condenser 67 is connected in parallel with contacts 63, 64 by wire 67^a and by a ground connection. Spring 68 connects a lug 69 of armature 61 with the fulcrum post 49.

When timer contacts 29, 30 close the holding coil 55 is short-circuited permitting coil 41 to act in the manner of a vibrator coil producing the vibration of armature 61 and the intermittent opening and closing of vibrator contacts 63, 64. The result is a shower of sparks at the plug 52. When the timer contacts 29, 30 separate, the short cir-

cuit around holding coil 55 is broken, consequently this coil will be energized sufficiently to hold armature 61 in attracted position and ignition at plug 52 will cease. Thus 5 it is apparent that ignition is produced at 52 only when the timer contacts 29, 30 are closed. The higher the engine speed, the shorter will be the timer contact closed period, hence the shorter the duration of the spark 10 shower at 52. The inductance of the coil 55 and the reluctance of the magnetic circuit of coil 55 is such that at a predetermined speed of the timer 29, the contact closed period is so short that there will not be 15 sufficient time for the armature 61 to be released from the holding coil while it is short-circuited. Hence above a certain speed armature 61 will remain in attracted position separating contacts 63, 64 as though the 20 timer contacts 29, 30 were continuously open. This action tends to save battery current and to render the burner ignition inoperative when it may not be necessary to use the burner when the engine has become 25 warmed up and has picked up in speed. The resistance of coil 55 is high enough that the engine ignition will not be interfered with to any substantial degree. Obviously this resistance must be high enough to insure a 30 reduction of current in coil 26 sufficient for sparking purposes at the engine plugs 33 when timer contacts 29, 30 are separated.

Figs. 2 to 5 show an embodiment of the ignition device 40 in a unitary structure. 35

Housing tube 70 rests on a base 71 supporting coil 41 and core 42. Core 42 includes a bundle of iron wires 72 and a center rod 73 engaging a nut 74 at its upper end and a nut 75 at its lower end. Nut 74 bears 40 against washer 76 in turn bearing against wires 72 and a non-conducting sleeve 77 in turn bearing against an end bell 41^a of coil 41. By tightening nuts 74 and 75 the core and coil assembly is secured upon the base 71. 45

The yoke 53 is attached to end bell 41^a and the holding coil core projects through a hole 78 in non-magnetic vibrator base 79, this hole being lined with a non-conducting washer 78^a as shown in Fig. 2. Thus core 50 54 is insulated electrically from the rest of the structure. The hole 80 in base 79 is to permit the upper end of core 42 to extend through it. The base 79 supports the fulcrum post 49 which is attached thereto by 55 tubular rivets 81 and 82 which are insulated from the base 79. A bracket 83 riveted to base 79 supports the adjusting screw 65. The base 79 is provided with a recess in which condenser 62 rests, this condenser being grounded on base 79 and secured thereto by clip 84 and screw 85. 60

As shown in Fig. 4, the housing tube 70 supports the terminals 59, 57 and 46 designated by CB (meaning "circuit breaker"), 65 G (meaning "ground") and B (meaning "battery"), respectively. Terminal G is attached to a metal clip 90 which makes contact with the base 79 when secured to tube 70. 70

The base 79 supports a vibrator cover 91 attached thereto by a nut 92 engaging a post 93 extending through said cover 91 and attached to the base 79. 75

While the form of mechanism herein shown and described constitutes a preferred form of embodiment of the invention, it is to be understood that other forms might be adopted, all coming within the scope of the claims which follow. 80

What I claim is as follows:

1. In an ignition system, the combination with engine ignition apparatus including a current source, ignition coil, an engine operated timer and an engine spark plug; of a vibrator ignition coil; an auxiliary spark plug connected to said vibrator coil and means associated with said vibrator coil and controlled by said engine timer for permitting the vibrator coil to be operative only when the timer contacts are closed. 90
2. In an ignition system, the combination with engine ignition apparatus including a current source, ignition coil, an engine operated timer and an engine spark plug; of a vibrator ignition coil including a core and vibrating armature; an auxiliary spark plug connected to said vibrator coil; and an auxiliary electromagnet associated with said armature and connected in shunt with said timer contacts for preventing operation of said armature when said timer contacts are opened. 95
3. In an ignition system, the combination with engine ignition apparatus including a current source, ignition coil, an engine operated timer and an engine spark plug; of a vibrator coil including a core and vibrating armature; an auxiliary spark plug connected to said vibrator coil; and an auxiliary magnet having a core in magnetic circuit with said vibrator coil core and armature and a winding in shunt with the timer contacts. 100
4. In a device of the character described, the combination with a housing having a removable closing member provided with openings; an ignition coil having a core located within said housing, and a controlling coil having a core located within said housing, both of said cores projecting through openings in said closing member; a vibrating armature supported by said closing member in proximity to said cores; a contact supported by said armature; and a contact supported by closing member. 110

In testimony whereof I hereto affix my signature.

AUGUST TOELLE.
